(57) **CLAIM**

The ornamental design for a kitchen slicer set, as shown and described.

DESCRIPTION

FIG. 1 is a top perspective view of the kitchen slicer showing my new design;

FIG. 2 is a side view thereof;
FIG. 3 is a opposite side view thereof;
FIG. 4 is a bottom plan view thereof;
FIG. 5 is a top plan view thereof;
FIG. 6 is an end view thereof;
FIG. 7 is an opposite end view thereof;
FIG. 8 is a top perspective view of an alternate embodiment of FIG. 1;
FIG. 9 is a top plan view of FIG. 8;
FIG. 10 is a bottom plan view of FIG. 8;
FIG. 11 is an end view of FIG. 8;
FIG. 12 is an opposite end view of FIG. 8;
FIG. 13 is a front perspective view of the slice portion shown separately for clarity of illustration;
FIG. 14 is a bottom perspective view of FIG. 13;
FIG. 15 is a top plan view of FIG. 13;
FIG. 16 is a bottom plan view of FIG. 13;
FIG. 17 is a side view of FIG. 13;
FIG. 18 is an opposite side view of FIG. 13;
FIG. 19 is an end view of FIG. 13;
FIG. 20 is an opposite end view of FIG. 13;
FIG. 21 is a rear perspective view of the cutter portion shown separately for clarity of illustration;
FIG. 22 is a top plan view of FIG. 21;
FIG. 23 is a bottom plan view of FIG. 21;
FIG. 24 is a side view of FIG. 21;
FIG. 25 is an opposite side view of FIG. 21;
FIG. 26 is an end view of FIG. 21;
FIG. 27 is an opposite end view of FIG. 21;
FIG. 28 is a top perspective view of an alternate cutter portion shown separately for clarity of illustration;
FIG. 29 is a bottom perspective view of FIG. 28;
FIG. 30 is a top plan view of FIG. 28;
FIG. 31 is a bottom plan view of FIG. 28;
FIG. 32 is a side view of FIG. 28;
FIG. 33 is an end view of FIG. 28; and,
FIG. 34 is an opposite end view of FIG. 28.
